ELECTRIC FUSE

Elmer L. Mason, Barnesville, Ohio

Application July 9, 1938, Serial No. 218,404

2 Claims. (Cl. 200—131)

This invention relates to electric fuses and particularly to that type of fuse known as the knife-blade contact type; and an object of the invention is, generally, to improve upon electric fuses of this character.

The invention together with its objects and advantages will be best understood from a study of the following description taken in connection with the accompanying drawings wherein:

10 Figure 1 is a view partly in section and partly in elevation showing the improved fuse,

Figure 2 is an elevational view of the fuse with parts broken away and shown in section,

15 Figure 3 is a view partly in section and partly in elevation of the fuse links and terminals therefor,

Figure 4 is an end elevational view of the fuse,

Figure 5 is an elevational view of the cover plate of the fuse casing,

20 Figure 6 is an elevational view of the fuse casing with the cover plate removed,

Figure 7 is a fragmentary detail sectional view illustrating a slightly modified form of the invention, and

25 Figure 8 is an end elevational view of the form of the invention shown in Figure 7.

Figure 9 is a detail view partly in section and partly in elevation showing an alternate manner of connecting a fuse link with its terminals.

30 Referring to the drawings by reference numerals it will be seen that in accordance with the invention the fuse per se consists of a pair of terminals 5 and 6 connected by a fuse link 7 of any desired type.

35 For connecting the fuse link 7 with its terminals 5 and 6 the terminals, as shown in Figure 3, are provided at one end with sockets 11 which receive the ends of the link 7. Threadedly engaged with one wall of the socket are clamping

40 screws 12 which at their inner ends are provided with enlarged disk-like heads that serve to clamp the fuse link at the ends thereof between the heads of the screws and the walls of the sockets 11 opposite to the walls of the sockets with which the screws 12 are threadedly engaged.

45 In the form of the invention suggested in Figure 9 the link 7 is connected at each end thereof with a terminal, only one of which, 5, is shown in Figure 9, through the medium of a U-shaped member 9 that straddles one wall of the socket 8 of the terminal, the end of the link 7 being clamped between one leg of the member 9 and a wall of the socket through the medium of a screw 10 that threads through the outer leg 50 of the U-shaped member 9, the wall of the socket

8 straddled by the U-shaped member, and at its inner end has bearing engagement with the inner leg of the U-shaped member 9 as shown in said Figure 9.

Also, in accordance with the present invention 5 there is provided a suitable casing for the fuse, and in both forms of the invention the casing indicated generally by the reference numeral 13 consists of an elongated hollow block of insulating material. The hollow block 13 provides an 10 elongated open front chamber 14 therein and is constructed and arranged with a pair of laterally spaced parallel ribs 13' in the rear of said chamber extending longitudinally from end to end of the block and forming therebetween an open 15 front central channel 15' enlarged at its ends, as at 15 and 16, so that said channel is wider and deeper at said ends thereof. The shallower and narrower intermediate portion of said channel 15' accommodates the link 7 therein and the ends 15 20 and 16 the sockets 11 of the terminals 5 and 6, respectively. A pair of slots 16' is provided in the ends 22 of the block 13, respectively, in the longitudinal center thereof, said slots being narrower than the ends 15 and 16 and opening onto 25 the front of the casing to snugly receive the terminals 5 and 6, respectively.

The casing 13 is closed at its front through the medium of a removable cover plate 18 of suitable insulation material.

30 The cover plate 18, as best shown in Figures 5 and 6, is of rectangular panel form to fit the open front of the casing 13 and is provided with a beveled edge, as at 18', fitting against a similar internal beveled edge 13'' on said casing 13, a 35 shoulder 18'' extending around the same for engagement with a complementary shoulder 13''' extending around said edge 13'' of casing 13, and a rib 19 fitting into the open front of said casing. The rib 19 is longitudinally concave, 40 as best shown in Figure 2, and at each end thereof is bifurcated to provide in the longitudinal center thereof a pair of end grooves 19', whereby said rib is adapted at the ends thereof to straddle the sockets 11 and terminals 5, 6, while the central 45 part of said rib arches away from the link 7 out of contact therewith. At the outer ends of the grooves 19' said edge 18' of the cover plate 18 has extending therefrom a pair of short key ribs 19'' adapted to fit into the outer ends of the 50 slots 16' as best shown in Figure 4.

At one end thereof the rib 19 is provided with a pair of integral teats 20 that are adapted to spring into openings 21 provided in one end 22 of the casing 13 while at the opposite end thereof 55

the rib 19 has suitably anchored thereto one end of spring latches 23 that are accommodated in recesses 24 provided therefor in said end of the rib. The spring latches 23 are provided with 5 integral teats 25 adapted to spring into engagement with openings 26 provided in the opposite end of the casing, all of which is clearly shown in Figure 2.

At the spring-latch equipped end thereof the 10 cover plate 18 is provided with a lip 28 adapted to be engaged by the finger in a manner to facilitate removal of the cover plate.

It will thus be seen that I have provided an 15 efficient casing of simple construction and design. With this casing, when a fuse burns out the cover 20 plate 18 is quickly and easily removed and a new fuse readily inserted therein after which the cover plate is again fastened in position.

It will be noted that in the form of the invention 25 shown in Figures 1 to 4 inclusive the ends 22, 27 thereof are integral with the body of the casing.

In the form of the invention shown in Figures 25 7 and 8, instead of having the end walls integral with the body of the casing, the casing at the opposite end thereof is open as at 29 and 30 respectively. Arranged within the openings 29 and 30 are metallic end plates 31, 32 and the plates are suitably slotted as at 33 to accommodate the 30 terminals 5 and 6.

Also to accommodate the plates 31, 32 the casing is provided adjacent the ends 29, 30 thereof with internal grooves 33 which accommodate the edges of the plates as shown.

35 Also as shown each of the plates 31, 32 is provided at opposite sides of the slot therein with openings 34 to accommodate the latch teats carried by the cover plate for releasably securing the cover plate in position on the case.

40 It is thought that a clear understanding of the construction utility and advantages of an electric fuse embodying the features of the present invention will be had without a more detailed description.

Having thus described the invention what is claimed as new is:

1. In a device of the class described, a pair of fuse terminals having an enlarged end socket, respectively, a flat fuse link secured at its opposite ends in said sockets, respectively, for connecting said terminals together, and a junction box for housing said sockets and link comprising an elongated hollow block having an open front for the insertion of said sockets and link therein, and 10 slotted ends for straddling said terminals beyond said sockets, said block having therein in the rear thereof a pair of laterally spaced ribs extending longitudinally from end to end thereof and constructed and arranged to form therebetween an 15 open front channel having enlarged ends for accommodating said sockets and a restricted intermediate portion for accommodating said link, and a detachable closure plate for the front of 20 said block.

2. In a device of the class described, a pair of fuse terminals having an enlarged end socket, respectively, a flat fuse link secured at its opposite ends in said sockets, respectively, for connecting said terminals together, and a junction box for 25 housing said sockets and link comprising an elongated hollow block having an open front for the insertion of said sockets and link therein, and slotted ends for straddling said terminals beyond said sockets, said block having therein in the rear 30 thereof a pair of laterally spaced ribs extending longitudinally from end to end thereof and constructed and arranged to form therebetween an open front channel having enlarged ends for 35 accommodating said sockets and a restricted intermediate portion for accommodating said link, and a detachable closure plate for the front of said block comprising a longitudinal rib fitting into said front, said rib being longitudinally concaved to clear the link intermediate the sockets and 40 bifurcated at the ends thereof to straddle said sockets, respectively, and thereby function to maintain the same in a common plane.

ELMER L. MASON.
